FILM CLIP

Walter H. Pieiss, Ludington, Mich., assignor to
Burke & James, Inc., Chicago, Ill., a corpora-
tion of Illinois

Application December 1, 1938, Serial No. 243,373

8 Claims. (Cl. 24—259)

Heretofore in clips for holding photographic films one of the jaws of the clip has been provided with tubular bosses and the other with pointed barbs which enter the bosses and when gripping the film between the jaws it has been necessary to exert pressure thereon to cause the clip to firmly grip the film to prevent its slipping, for the reason that the barbs have all been of the same length.

10 In the present invention, however, this objection has been overcome by providing barbs or teeth of different lengths so that when the film is gripped between the jaws, the spring of the clip will cause the larger barbs to penetrate the film

15 first and will be followed by the engagement of the film by the shorter barbs, thereby obviating the necessity of exerting pressure upon the clip.

Heretofore another serious objection is present with the former clips in that the jaws themselves will form a pocket which will retain a small amount of water, with the result that after the film has become dry and the clips are opened to detach the film therefrom, the water retained between the jaws will run down upon the dried film, which is very objectionable.

To overcome these objections and difficulties and to provide an improved film clip of this character in which means are provided for preventing the slipping of the film and of the formation of the sharp projection, is one of the objects of the present invention.

A further object is to provide improved means whereby the clips may be placed upon a supporting line or wire without interfering with the other clips that are suspended thereby, and at the same time obviate the necessity of stringing the clips upon the line, which latter operation results in the objection that the films will be brought into contact by the sliding of the clips along the supporting line.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

50 Figure 1 is a top plan view of a clip of this character constructed in accordance with the principles of this invention.

Figure 2 is a bottom plan view of the clip.

Figure 3 is a front end elevation of the clip.

55 Figure 4 is an edge view of the clip.

Figure 5 is a view similar to Figure 3 with the jaws of the clip separated.

Figure 6 is a view taken on line 6—6, Figure 1, on an enlarged scale.

Figure 7 is a view similar to Figure 6 showing another form of clip.

Referring more particularly to the drawing, the clip consists essentially of two body members 10—11 which may be formed separately from each other and connected together as at 12, or 10 may be formed of a single piece of material bent into shape. The forward portions of the jaws 10—11 are bent towards each other as at 12—13 so that they will cross, and in the portion 12 of the member 10 there is provided a slot 14 through 15 which the portion 12 of the member 11 passes.

The extremity 15 of the portion 12 is bent forwardly into a substantially horizontal plane and is provided with a plurality of tubular conical bosses 16 laterally spaced from each other to 20 form recesses or spaces 17 therebetween.

The extremity of the portion 13 of the member 11 is bent forwardly as at 18 and then at substantially right angles to the portion 18, as at 19.

The edge of the portion 19 is provided with 25 teeth or barbs 20, laterally spaced from each other and positioned so that when the jaw members are closed they will enter the openings in the tubular bosses 16.

One of these teeth or barbs 20 is provided for 30 each of the conical projections 16.

The edge of the jaw 19 is also provided with teeth or barbs 21 which are preferably of a greater length than the teeth or barbs 20 and arranged intermediate the latter so as to enter the 35 spaces 17 between adjacent tubular bosses 16 to contact the jaw 15. With this arrangement it will be manifest that when a film is placed between the jaws when the latter are held open against the resilient action of the body members 40 10—11 it will rest upon the apexes of the conical bosses 16.

When the jaws are released the spring tendency of the body portions 10—11 will cause the jaws 45 to move into contact with the result that the longer barbs or projections 21 will contact and grip the film 22 before the shorter barbs 20 co-operate with the tubular bosses to grip the film. The shorter barbs will force portions of the film into the bosses, as at 23, while the longer barbs or projections 21 which are intermediate the barbs or projections 20 will co-operate with the portion of the jaw 15 between the bosses to further grip the film, as at 24 and at the same 50 55

time limit the movement of the jaws of the clip towards each other.

5 The barbs or projections 21 being of a length greater than the barbs or projections 20 will initially force portions of the film into the spaces between the bosses 16 before the barbs or projections 20 engage the film.

10 With this form of the invention it will be manifest that the film will not be perforated and the extent to which the barbs 20 and the bosses 16 grip the film will be controlled by the barbs or projections 21 contacting the jaw 15. The barbs or projections 20 may be of any desired configuration.

15 In the end 25 of the body portion of the clip there is provided a slot or recess 26 which opens through the end thereof and this recess at its inner end is enlarged, as at 27, to provide an overhanging and undercut lip 28 that is spaced a 20 substantial distance from the entrance end of the slot.

25 This slot is provided for the purpose of stringing the clips upon a supporting wire or line to obviate the necessity of having to thread them thereupon. This latter operation results, when additional clips are threaded upon the line, in causing the films to be moved into contact with each other which is not desirable.

30 With the present invention the clip can be fastened upon the supporting line very readily by causing the line to enter the slot 26 into the seat 27 and then moving the clip so that the overhanging and undercut lip 28 will engage and rest upon the line.

35 In Figure 7 there is shown another form of the invention in which the jaw 19 is provided with barbs 29—30 that are pointed, the barbs 29 being somewhat longer than the barbs 30, each of the barbs being adapted to enter one of the conical bosses 16. The longer barbs 29 are preferably 40 located between the shorter barbs 30. In this form of the invention the longer barbs 29 will penetrate the film 22 first to hold the film from slipping and the tendency of the spring of the body portion of the clip will be to subsequently 45 cause the shorter barbs to penetrate the film.

50 It has been found that in clips of this character water accumulates between the jaw when the film is suspended by the clip with the result that after the film is dry and when the clip is opened the water will run down upon the dried film and spoil the same. By the provision of openings 31 in the jaw 19 water will be prevented from accumulating and will drain out through these 55 openings.

60 While the preferred forms of the invention have been herein shown and described, it is to be understood that various changes may be made in the details of construction and in the combination and arrangement of the several parts, within the scope of the claims, without departing from the spirit of the invention.

What is claimed as new is:

1. A film clip embodying co-operating jaws, one 65 of the jaws being provided with laterally offset tubular bosses, the other jaw being provided with spaced projections adapted to enter the respective bosses, and means carried by one of said jaws and adapted to contact the other jaw for limiting the extent to which the said projection will enter 70 said bosses.

2. A film clip embodying co-operating jaws, one of the jaws being provided with laterally offset

tubular bosses, the other jaw being provided with spaced projections adapted to enter the respective bosses, and means carried by one of said jaws and adapted to contact the other jaw for limiting the extent to which the said projection will enter said bosses, the said means embodying additional projections on the second recited jaw adapted to contact the other jaw outside of said bosses.

3. A film clip embodying co-operating jaws, one of the jaws being provided with laterally offset tubular bosses, the other jaw being provided with spaced projections adapted to enter the respective bosses, and means carried by one of said jaws and adapted to contact the other jaw for limiting the extent to which the said projection will enter said bosses, the said means embodying additional projections on the second recited jaw adapted to contact the other jaw outside of and intermediate said bosses.

4. A film clip embodying co-operating jaws one of which is provided with laterally offset tubular bosses, the other jaw being provided with a set of projections adapted to enter said bosses, an additional set of projections on the last said jaw 25 intermediate the first said projections for engagement with the other jaw outside of said bosses to limit the extent to which the first said set of projections will enter the said bosses, one of the said sets of projections being of a greater 30 length than the other set.

5. A film clip embodying co-operating jaws, one of the jaws being provided with laterally offset tubular bosses, the other jaw being provided with spaced projections adapted to enter the respective bosses, said projections being of unequal 35 length whereby when the film is gripped between the jaws the longer projections will perforate the film before the shorter projections engage the film.

6. A film clip embodying co-operating jaws, one of the jaws being provided with laterally offset tubular bosses, the other jaw being provided with spaced projections adapted to enter the respective bosses, said projections being of unequal 45 length whereby when the film is gripped between the jaws the longer projections will perforate the film before the shorter projections engage the film, the shorter projections being disposed on each side of the longer projections.

7. A film clip embodying co-operating jaws, one of the jaws being provided with laterally offset tubular bosses, the other jaw being provided with spaced projections adapted to enter the respective bosses, said projections being of unequal 55 length whereby when the film is gripped between the jaws the longer projections will perforate the film before the shorter projections engage the film, the jaw which carries the said projections being provided with cut away portions to permit 60 the escape of water from between the jaws.

8. A film clip embodying co-operating jaws, one of the jaws being provided with laterally offset tubular bosses, the other jaw being provided with spaced projections adapted to enter the respective bosses, said projections being of unequal 65 length whereby when the film is gripped between the jaws the longer projections will perforate the film before the shorter projections engage the film, there being water escape openings between 70 the extremities of one of the jaws.

WALTER H. PLEISS.
